UNITED STATES PATENT OFFICE.

GEORGE C. SNYDER, OF NEW YORK, N. Y.

MECHANICAL MOVEMENT.

Application filed March 6, 1920. Serial No. 363,823.

To all whom it may concern:

Be it known that I, GEORGE C. SNYDER, a citizen of the United States, residing at New York city, in the county of New York, State of New York, have invented certain new and useful Improvements in Mechanical Movements; and I do hereby declare the following to be a full, clear, and exact description of the invention, such as will enable others skilled in the art to which it appertains to make and use the same.

This invention which relates to mechanical movements has for its object the production of mechanical movements particularly adapted for controlling the operation of various elements of a machine, or mechanisms associated with the machine, from a moving part of the machine. The invention may be embodied in apparatus of simple construction involving the employment of a relatively small number of moving parts, and eliminating the use of complicated systems of cams, eccentrics, gears and levers which are commonly employed for effecting the automatic control of machinery.

The objects of the invention are attained by the provision of a member to which an intermittent movement may be directly imparted from a moving part of the machine, and which is adapted during its movement to actuate members which are connected to various parts of the apparatus that it is desired shall be under the control of the intermittently moving member. For the purpose of providing additional controls there is associated with this member a reciprocating member which may be initially actuated by the same moving part of the machine that actuates the main controlling member, but which after its initial actuation to perform a controlling operation is taken out of operative relation with the element of the machine which causes such initial actuation and remains in such inoperative relation until it is subsequently required to perform another controlling operation, at which time it is restored to operative relation to the part of the machine by which it is actuated, by means under the control of the intermittently moving member when the latter reaches a predetermined point in its movement.

The particular nature of the invention, as

well as other objects and advantages thereof, will appear more clearly from an illustration 55 and description of certain preferred embodiments, as shown in the accompanying drawings. Since the mechanical movements of the invention are of general utility they have not been shown in combination with any 60 particular machine. In the drawings, Fig. 1 is a perspective view of the mechanism with the members adapted to control the elements of a machine broken away; Fig. 2 is a plan view of certain elements of the 65 mechanism in their operative position; Fig. 3 is a corresponding view of the same elements in inoperative position; and Fig. 4 is a view in elevation of the same elements of the mechanism, viewed from the left-hand 70 side of Figs. 2 or 3; and Fig. 5 is a modification in which the controlling spindle is arranged to move horizontally.

Referring to the drawings, 10 indicates a portion of the frame of a machine, the elements of which are to be controlled by the mechanical movements of the invention. The frame is provided with bearings 11 which carry a main shaft 12 by which the machine is operated, this shaft being provided with a pulley 13 driven by a belt 14 from line shafting provided with a clutch or other suitable mechanism adapted to be controlled by a handle 15, which as will appear more clearly hereinafter is under the 85 control of the mechanism of the invention.

The controlling mechanism may be actuated from any desired moving element of the machine, but as shown herein it is controlled from the main shaft 12 by means of 90 a collar 16 adjustably attached to the shaft and provided with a tooth 17, which upon each rotation of the shaft engages and lifts a spindle by means of a series of conical ratchets 18 formed on the spindle and of 95 sufficient number to permit the spindle to perform all of its controlling functions. By making the ratchets of conical shape the spindle may be turned from time to time to bring different portions of the faces of the 100 ratchets into engagement with the tooth 17, thus lessening the wear upon them. The spindle is guided by a cylindrical member 20 mounted on the frame of the machine. The lower end of the spindle is extended as 105 19 and enters an aperture in a stop mem-

ber 20 which is carried at the upper end of a screw 21 mounted in a bracket 22 attached to the frame of the machine, the screw being provided with a member 23 by means of which its position in the bracket may be adjusted.

For the purpose of holding the spindle after each successive actuation, there is provided a spring-pressed pawl 24, the shank of which passes through a bracket 25 carried upon a framework 26 of the machine. Connected to the outer end of the shank of the pawl is an arm 27 attached to a shaft 28 which may be rotated by means of a link 29 connected to a pedal 30, the arrangement of the parts being such that when the pedal is depressed the arm 27 will be swung in a direction to release the pawl and withdraw it from the ratchet with which it is in engagement to permit the spindle to fall onto the stop 20.

The frame 26 is provided with guides 31 and 32 within which is mounted a bar 33 provided on its lower face with lugs 34 and 35 which are adapted to be engaged by teeth 36 and 37, respectively, on collars 38 and 38' adjustably attached to the main shaft 12. The bar 33 is provided with a longitudinal slot 39 by means of which blocks 40 and 41 may be adjustably attached to the bar. These blocks are provided with inclined faces adapted to cooperate with rollers 42 and 43 carried between the opposite ends of arms 44 attached to a shaft 45 mounted in suitable bearings on the frame of the machine. A collar 46 carrying an arm 47 is mounted upon the shaft 45, and the arm is connected by means of a link 48 to an arm 49 on a shaft 50 leading to one of the elements of the machine that requires to be controlled in timed relation to the other parts of the machine. A similar arm 51 and connecting rod 52 may be employed for controlling by means of a shaft 53 another element of the machine. It will be understood that other elements of the machine may, if desired, be controlled from the shaft 45 by means of other connections.

The front end of the bar 33 is provided with an extension 54 carrying at its end a handle 55 by which the bar may be manually manipulated if desired, and also a pin 56 fitting within a continuous slot 57 in a plate 58 carried upon suitable standards projecting from the frame member 10 of the machine.

Projecting from the edge of the bar 33 is a pin 60 adapted to be engaged by a spring-pressed latch 61 mounted upon the frame of the machine. Immediately in the rear of the pin 60 the bar is extended as at 62 to provide a member which will engage the latch 61 and compress its spring as the bar is moved forward. The opposite end of the bar 33 is widened as indicated at 63 to provide an inclined face adapted to be engaged

by a spring-pressed latch 64' mounted at the end of the frame member 26.

It is intended that the bar 33 shall be pulled out of its normal position by means of a spring 64 connected to the bar and to the frame of the machine. A second spring 65 is connected between the bar and the frame member 66 of the machine so as to pull the bar rearwardly when it is released as will appear more clearly hereinafter.

For the purpose of restoring the bar to its normal position after it has been moved by the springs, there is provided a lug 67 which may be adjustably connected to the bar by means of a bolt passing through the slot 39. The lug 67 carries a disc 68 rotatively mounted upon a pin 69 extending between a forked member 70 carried upon the end of a rod 71 and beneath which is a shoulder 72 adapted to engage the edge of the disc 68 to impart movement to the bar 33 through the lug 67. The other end of the rod 71 is connected by means of a universal joint 73 to the end of an arm 74 which is attached to a shaft 75 mounted in suitable bearings in the frame of the machine and adapted to be held in a normal position by means of a spring 76 connected at one end to an arm 77 attached to the shaft and at the other end to a pin 78 projecting from the frame of the machine. A stop 75' engaged by the arm 77 limits the movement of the shaft. The shaft 75 also carries an arm 79 which at its outer end is connected to a rod 80 attached to a lever 81 pivotally mounted upon a standard 82 attached to the frame member 10. The other end of arm 81 carries a forked member 82' provided with rollers adapted to be engaged by a collar 83 which is adjustably mounted on a threaded portion 84 of the spindle.

The portion 85 of the spindle lying above the portion 84 is also threaded, but is of lesser diameter. A nut 86 is mounted upon the threaded portion 85 and is adapted to engage and swing an arm 87 which may be used for controlling another element of the machine that should be brought into or taken out of action in timed relation to the other elements of the mechanism.

The handle 15 by which the transmission of power to the machine is controlled is also arranged so that it may be released by means of the spindle, in order to stop the machine after its several elements have performed their functions under the control of the ratchet spindle. For this purpose the end of the handle 15 carries a stirrup-shaped member 88 through which passes a shaft 89 mounted in suitable brackets in the frame of the machine and carrying a member 90 provided with a latching tooth 91 adapted to engage one side of the stirrup 88 when the handle 15 is moved forwardly into the position it occupies when the clutch is thrown to permit

power to be transmitted to the main shaft 12. A spring 92 connected between the handle 15 and the frame of the machine automatically throws the handle into position to disconnect the clutch and thereby stop the machine when the handle 15 is released from the latch 91. When the machine is in operation the latch 91 is normally held in position to engage the stirrup member 88 on the end of the rod by means of a spring 93 connected between the framework of the machine and an arm 94 carried upon the shaft 89. The shaft 89 also carries an arm 95 which is connected by means of a link 96 to one end of a bell crank lever 97 pivoted as at 98 at the upper end of the standard 82 and provided at its other end with a collar 99 surrounding the portion 85 of the spindle and adapted to be engaged by the upper end of the threaded portion 84 of the spindle as the latter is lifted.

In considering the operation of the mechanism described above, it will be assumed that the several elements thereof are in the position indicated in Fig. 1 with the spindle occupying its lowermost position, that is, with its extension 19 in the stop member 20. The machine with which the mechanism is associated will be started into operation by pulling the clutch-controlling handle 15 until its stirrup 88 snaps over the latch 91, the shaft 89 being held in position by spring 93 to cause the lug to engage the stirrup. As the main shaft 12 rotates, the tooth 17 will engage the ratchets 18 to lift the spindle one step for each rotation of the shaft. The spindle will be held in successive elevated positions by means of the pawl 24. The first rotation of the shaft will also cause the tooth 37 to engage the lug 35 attached to the lower face of the bar 33 to advance the same and bring the inclined block 41 into engagement with the roller 42 to rock the shaft 45 and impart movement to the rods 50 and 53 which lead to elements of the machine that should be put into operation during the first revolution of shaft 12. During the forward movement of the bar 33 the inclined face of the projection 62 will engage the latch 61 to swing the latter against the spring. The lug 62 is of such length and so positioned with respect to the other parts of the apparatus that the latch engages the outer edge of the lug when the pin 56 reaches the front corner of the slot 57. At this time the spring associated with the latch is under compression so that when the pin 56 reaches the corner of the slot the spring will force the bar 33 out of its straight line of travel. The effect of the spring associated with the latch will also be reinforced by the pull exerted by the spring 64, and the spring 65 will also tend to draw the bar 33, so that under the combined effect of the springs the bar will finally assume a position such as

shown in Fig. 3 with the latch 64' in engagement with the face of the extension 63 at the end of the bar.

The travel imparted to the forward end of the bar 33 as the pin 56 travels through the slot 57 will be sufficient to carry the inclined block 40 from a position in front of the roller 42, around the side of the roller and into a position such as indicated in Fig. 3, so that when the bar is restored to its initial position the inclined block will be in position to engage the roller 42 as will appear more clearly hereinafter.

As the spindle is successively raised by each rotation of the shaft 12, the nut 86 comes into engagement with the arm 87 to swing the latter and put into operation the elements of the machine controlled thereby. Further elevation of the spindle will finally bring the nut 83 into engagement with the rollers 82' on the end of lever 81 to swing the latter, and through the rod 80 and arm 79 rock the shaft 75 and swing the arm 74 so that by means of the rod 71 the shoulder 72 will be brought into engagement with the disc 68 and through the lug 67 push the bar 33 against the effect of the springs 64 and 65 until it has been restored to its operative position. The parts should be so proportioned that when the bar 33 occupies its normal position the rod 71 and arm 74 will lie in alinement, so that should there be any further rotation of the shaft 75 the arm and rod will be moved beyond their alined position to prevent them from exerting any further pressure upon the bar 33 with possible injury to the parts of the mechanism. As the bar swings, the latch 64' will be disengaged from the inclined face at the rear of the bar, and the inclined block 40 will be brought into position behind the roller 42 while the lug 34 attached to the bar will be in position to be engaged by the tooth 36 as the main shaft 12 rotates. The forward movement thus imparted to the bar 33 will draw the inclined block 40 under the roller 42 to rock the shaft 45 in a direction opposite to that in which it was rocked by the inclined block 41, so as to rotate the shafts 50 and 53 in such manner as to move the elements of the machine in a reverse direction to that in which they were moved by the initial action of these rods. After the bar 33 has moved forward sufficiently to cause the inclined block 40 to rock the shaft 45, the pin 60 will be brought in front of the latch 61 to hold the bar in its forward position against the retractive effect of spring 65. In the mechanism shown herein the inclined block 40 is provided with an intermediate flat portion so that the main controlling movement imparted to the shaft 45 through roller 42 will after a brief interval, depending upon the length of the flat portion, be followed by a slight additional move-

ment to effect another controlling operation before the inclined block passes from under the roller.

After the ratchet spindle has performed its function of restoring the bar 33 to the initial position, as explained above, the upper end of the portion 84 of the spindle will subsequently be brought into engagement with the collar 99 to swing the lever 97, and through rod 96 and arm 95 rotate the shaft 89 against the effect of spring 93 to disengage the tooth 91 from the stirrup member 88 on the end of the clutch-controlling handle 15, so that the latter will be restored to non-operative position by its spring 92 and disconnect the machine from its source of power.

In order to restore the controlling mechanism to a starting position, preparatory to a subsequent operation of the machine, it is only necessary to actuate the pedal 30 to withdraw the pawl 24 from engagement with the ratchet of the spindle with which it is in contact, so as to permit the spindle to fall upon the stop member 20, whereupon the lever 81 will be released so that spring 76 may swing the shaft 75 into the position indicated in Fig. 1. Lever 97 will also be released to permit spring 93 to rock the shaft 89 to bring the latch 91 in position to engage the stirrup member 88 when the handle 15 is drawn forward for the operation of the machine.

In some cases it may be advantageous to arrange the controlling spindle to move horizontally instead of vertically, and in Fig. 5 there is shown such a modification of the invention. In this arrangement the spindle is slidably mounted in a guide 100, and is adapted to be advanced by a tooth on the main shaft 12, which engages the ratchets 18 on the spindle. A stop member 101 is adjustably mounted upon guideways 102 associated with the frame of the machine. The stop member is provided with a bore through which passes a cord 103 attached at one end to the end of the spindle. The cord passes over a pulley 104, and a weight 105 is attached to its other end. A pawl 24 is provided for holding the spindle against the effect of the weight 105, after it has been advanced by the tooth on the main shaft 12. This pawl may be released from engagement with the spindle by means of a treadle, as in the modification of the invention shown in the preceding figures.

In order to simplify the drawing the various elements adapted to be controlled by the spindle have not been shown in detail in Fig. 5, as it will be clear that the spindle may be provided with collars 106 adapted to engage arms 107 connected to shafts by which the elements of the machine may be controlled. It will also be understood that 65 a controlling bar such as 33 of the preceding

figures may be used in conjunction with the horizontally arranged spindle of Fig. 5, and that such bar may be used for controlling elements of the machine in the manner previously described.

The mechanical movements constituting the invention are particularly adapted for controlling machines for manufacturing articles in which certain rotations of the main shaft 12 produce steps in the operation of manufacture. By adjusting the position of the stop member 20 and the position of the nuts 83 and 86 on the spindle, the number of successive operations that will be performed upon the article being manufactured may be predetermined by the number of ratchets 18 that will be successively engaged by the tooth 17 before the end of the portion 84 of the spindle is brought into engagement with the collar 99 on the end of lever 97 to stop the machine, and the timing may be governed by the position of tooth 17 in its relation to shaft 12. The mechanism also insures that the same number of steps will be performed upon each of the articles being manufactured and at identical times in the case of each article. After each article has been manufactured the spindle may be restored to its position upon stop member 20, so that during a subsequent operation of the machine the movement imparted to the spindle before it comes into position to stop the machine will be the same as in the preceding operation, and the various elements of the machine that are under the control of the mechanism of the invention will be actuated in the same predetermined timed relation to each other for each article manufactured. The time relation between the controlling functions performed by the spindle and those performed by the bar 33 may, however, be altered by changing the relative position of the collars 16, 38 and 38' upon the main shaft of the machine.

The construction possesses the further advantage that if at any time while the machine is running, it is desired to change the number of functions being performed by the machine, the spindle may be manually lifted between successive functions, so that the portion thereof which stops the machine will be brought into action in advance of its normal time, with the result that a lesser number of operations are performed upon the article being manufactured, but the control over the elements of the machine effected by the upward movement of the spindle will take place in the manner described. In case it is desired to increase the number 115 of functions being performed by the machine while it is running, the pawl 24 may be released by depressing the pedal 30 so as to allow the spindle to fall back to its position upon the stop member 20, so that a 120

correspondingly increased number of successive upward movements must be imparted to the spindle before it exercises its function in controlling the elements of the machine and ultimately stopping the machine.

I claim:

1. In a mechanical movement for controlling the operation of a machine, the combination of a controlling member, means for imparting a step-by-step movement to the member, and means associated with the member and adapted to actuate controlling elements of the machine as the member is advanced.
- 10 2. A mechanical movement adapted to control the operation of a machine, comprising a member provided with a ratchet, means associated with the machine to be controlled and adapted to cooperate with the ratchet for advancing the member, and means associated with the member and adapted to actuate controlling elements of the machine as the member is advanced.
- 15 3. A mechanical movement adapted to control the operation of a machine, comprising a controlling member, means associated with the machine to be controlled for advancing the member, means associated with the member for actuating controlling elements of the machine as the member is advanced, a second controlling member, means associated with the machine to be controlled for actuating the second controlling member to perform a controlling function upon the machine, means for taking the second controlling member out of operative relation to the machine, and means under the control of the first named controlling member for restoring the second controlling member to operative relation to the machine.
- 20 4. A mechanical movement adapted to control the operation of a machine, comprising a controlling member, adapted to be actuated by the machine to be controlled for performing controlling functions upon the machine, a second controlling member adapted to be actuated by the machine for performing additional controlling functions, means for taking the second controlling member out of operative relation to the machine, and means under the control of the first named controlling member for restoring the second controlling member to operative relation to the machine to permit it to perform controlling functions.
- 25 5. In a mechanical movement for controlling the operation of a machine, the combination of a member provided with conical ratchet teeth, a pawl associated with the machine to be controlled for advancing the member, means for holding the member in successive advanced positions, and means associated with the member for actuating controlling elements of the machine.
- 30 6. In a mechanical movement for controlling the operation of a machine, comprising a member provided with conical ratchet teeth, a pawl associated with the machine to be controlled for advancing the member, means for holding the member in successive advanced positions, and means associated with the member for actuating controlling elements of the machine.
- 35 7. In a mechanical movement for controlling the operation of a machine, comprising a member provided with conical ratchet teeth, a pawl associated with the machine to be controlled for advancing the member, means for holding the member in successive advanced positions, and means associated with the member for actuating controlling elements of the machine.
- 40 8. In a mechanical movement for controlling the operation of a machine, the combination of a member to which a step-by-step movement may be imparted from a rotating element of the machine, means associated with the member for actuating controlling elements of the machine, a stop adapted to be engaged by the member, and means for adjusting the stop to determine the initial position of the member with respect to the controlling elements of the machine that are actuated by the advance of the member.
- 45 9. In a mechanical movement for controlling the operation of a machine, the combination of a member to which a step-by-step movement may be imparted from a rotating element of the machine, a stop against which the member may be drawn by gravity, and means for adjusting the stop to determine the initial position of the member with respect to the controlling elements of the machine that are actuated by the advance of the member.
- 50 10. A mechanical movement comprising a spindle provided with ratchets, means adapted to engage the ratchets successively to advance the spindle, a bar, means for advancing the bar longitudinally, means for moving the bar laterally after it has been advanced, and means under the control of the spindle for restoring the bar to normal position.
- 55 11. A mechanical movement comprising a spindle provided with ratchets, means adapted to engage the ratchets successively to advance the spindle, a bar, means for advancing the bar, means for guiding the bar while it is being advanced to cause it to move longitudinally, said guiding means being arranged to permit the bar to move laterally after it has been advanced, means for imparting lateral movement to the bar, and means under the control of the spindle for restoring the bar to normal position.
- 60 12. A mechanical movement comprising a spindle provided with ratchets, means adapted to engage the ratchets successively to advance the spindle, a bar, means for advancing the bar, means for guiding the bar while it is being advanced to cause it to move longitudinally, said guiding means being arranged to permit the bar to move laterally after it has been advanced, means for imparting lateral movement to the bar, and means under the control of the spindle for restoring the bar to normal position.
- 65 13. A mechanical movement for controlling the operation of a machine, the combination of a member provided with conical ratchet teeth, a tooth associated with the machine to be controlled for advancing the member, means associated with the member for actuating controlling elements of the machine, and an adjustable stop adapted to be engaged by the member to determine the initial position thereof.

ling the operation of a machine, the combination of a member provided with conical ratchet teeth, a tooth associated with the machine to be controlled for advancing the member, means associated with the member for actuating controlling elements of the machine, and an adjustable stop adapted to be engaged by the member to determine the initial position thereof.

7. In a mechanical movement for controlling the operation of a machine, the combination of a member provided with conical ratchet teeth, a tooth associated with the machine to be controlled for advancing the member, means for holding the member in successive advanced positions, means for releasing the holding means, means for limiting the movement of the member when it is released, and means associated with the member for actuating controlling elements of the machine.

8. In a mechanical movement for controlling the operation of a machine, the combination of a member to which a step-by-step movement may be imparted from a rotating element of the machine, means associated with the member for actuating controlling elements of the machine, a stop adapted to be engaged by the member, and means for adjusting the stop to determine the initial position of the member with respect to the controlling elements of the machine that are actuated by the advance of the member.

9. In a mechanical movement for controlling the operation of a machine, the combination of a member to which a step-by-step movement may be imparted from a rotating element of the machine, a stop against which the member may be drawn by gravity, and means for adjusting the stop to determine the initial position of the member with respect to the controlling elements of the machine that are actuated by the advance of the member.

10. A mechanical movement comprising a spindle provided with ratchets, means adapted to engage the ratchets successively to advance the spindle, a bar, means for advancing the bar longitudinally, means for moving the bar laterally after it has been advanced, and means under the control of the spindle for restoring the bar to normal position.

11. A mechanical movement comprising a spindle provided with ratchets, means adapted to engage the ratchets successively to advance the spindle, a bar, means for advancing the bar, means for guiding the bar while it is being advanced to cause it to move longitudinally, said guiding means being arranged to permit the bar to move laterally after it has been advanced, means for imparting lateral movement to the bar, and means under the control of the spindle for restoring the bar to normal position.

12. A mechanical movement comprising a reciprocating member, means for imparting a step-by-step movement to the member, a bar, means for advancing the bar longitudinally, springs for moving the bar laterally and retracting the same after it has been advanced, and means actuated by the reciprocating member for overcoming the effect of the springs and restoring the bar to normal position. 60
13. A mechanical movement comprising a reciprocating member, means for imparting a step-by-step movement to the member, a bar, means for advancing the bar longitudinally, springs for moving the bar laterally and retracting the same after it has been advanced, a member adjustably attached to the bar, a disc rotatably mounted on the member, a rod formed at its end to engage the edge of the disc, a shaft, means connected to the shaft and adapted to be actuated by the reciprocating member for rotating the shaft, and an arm connected to the shaft and the rod for actuating the latter to overcome the springs and restore the bar to normal position, the arm and rod being so proportioned that when the bar is in normal position they will lie in alinement with each other. 70
14. In a mechanical movement for controlling the operation of a machine, the combination of a controlling member, means associated with the machine for imparting a step-by-step movement to the member, a shaft, means associated with the shaft for actuating controlling elements of the machine, a bar, means associated with the machine for advancing the bar, means mounted on the bar for swinging the shaft as the bar is advanced, means for taking the bar out of operative relation to the advancing means, and means adapted to be actuated by the controlling member for restoring the bar to normal position, and means mounted on the bar and adapted to be brought into position, when the bar is restored to normal position, to swing the shaft in the opposite direction upon a subsequent advance of the bar. 80
15. In a mechanical movement for controlling the operation of a machine, the combination of a controlling member to which a step-by-step movement may be imparted from a continuously rotating element of a machine, means associated with the member for successively actuating controlling elements of the machine as the member is advanced, a second controlling element adapted to be initially actuated by the same continuously rotating element of the machine to perform a controlling function, means for taking the second controlling element out of operative relation to the rotating element, and means adapted to be actuated by the first controlling member when it reaches a predetermined point for restoring the second controlling member to operative relation to the rotating element so that another controlling operation may be performed. 90
16. In a mechanical movement for controlling the operation of a machine, the combination of a member to which a step-by-step movement may be imparted from a rotating element of the machine, a member adjustably mounted upon the first named member, and adapted to contact at a predetermined time during a step movement with another member for performing an automatic function. 100
17. A mechanical movement comprising a rod provided with ratchets, a shaft, a tooth mounted on the shaft and adapted to advance the rod a step for each revolution of the shaft, means for holding the rod in advanced position after each step, and means adjustably connected with the rod for performing automatic functions during the advance of the rod at predetermined stages of such steps. 90
18. A mechanical movement comprising a ratchet rod actuated by a tooth mounted on a rotating member to produce a step movement for each rotation, means connected with the rod for producing automatic functions at predetermined stages of the steps through members adjustably mounted upon the rod, and means for adjusting the position of the tooth in its relation to the rotating member. 100
19. In a mechanical movement the combination of a main shaft, a spindle provided with ratchets, means adjustably mounted on the shaft and adapted to engage the ratchets successively to advance the spindle, a bar, means adjustably mounted on the main shaft for initially advancing the bar longitudinally, means for moving the bar laterally after it has been advanced, and means under the control of the spindle for restoring the bar to normal position. 110

In testimony whereof I affix my signature.

GEORGE C. SNYDER.
